WITNESS:

ATTORNEY

UNITED STATES PATENT OFFICE

WALTER A. BISHMAN, OF MINNEAPOLIS, MINNESOTA

STORAGE-BATTERY CARRIER

Application filed December 17, 1927. Serial No. 240,787.

This invention relates to handles for storage batteries and its general object is to provide a detachable handle that can be easily and expeditiously associated with any type 5 and make of storage battery whereby the battery can be conveniently handled with very little effort.

Another object of the invention is to provide a storage battery handle including jaws 10 that are urged into cooperative association for gripping parts of the battery in a manner whereby manual movement of the jaws is necessary to remove the same from the parts.

15 This invention also consists in certain other features of construction and in the combination and arrangement of the several parts, to be hereinafter fully described, illustrated in the accompanying drawings and specifically pointed out in the appended claims.

20 In describing my invention in detail, reference will be had to the accompanying drawings wherein like characters denote like or corresponding parts throughout the several 25 views, and in which:

Figure 1 is a side elevation of the handle forming the subject matter of the present invention with parts broken away and in section.

30 Figure 2 is a side elevation of the handle and showing the same applied to a storage battery.

Figure 3 is a similar view taken at right angles to Figure 2.

35 Referring to the drawings in detail, the reference numeral 1 indicates the body of the handle and the body is round in cross section so as to provide a convenient gripping surface as will be apparent. The body is recessed

40 to provide bifurcated ends 2 and communicating with these recesses and arranged longitudinally in the body is a bore 3. Pivotedly secured between the respective portions of the bifurcated ends 2 through the medium of

45 pivot pins 4 are one of the ends of shanks 5 which are twisted intermediate their ends as at 6 so as to provide the jaw carrying portions 7 thereof at right angles to the pivoted ends as best shown in Figure 1 of the drawings. The jaw carrying ends are bent to-

ward each other to provide jaws 8 which have upwardly inclined flanges 9 formed on their confronting ends. The flanges 9 terminate in sharpened free ends as shown.

The said jaw carrying portions 7 which are twisted from shanks 5 extend outwardly and oppositely and at a slight angle to the longitudinal center lines of said shanks in order that the jaws 8 may be offset relatively to each other, rather than disposed in alignment to engage the offset connectors of a storage battery.

Arranged in the bore 3 and having one of its ends secured to one of the shanks 5 is a coil spring 10 which has its opposite end fixed 65 to a fiber block 11 of insulating material, and the other shank 5 is connected with the block 11 through the medium of a link 12.

From the above description and disclosure of the drawings, it will be obvious that I have 70 provided a handle which may be easily associated with a storage battery in a manner whereby the jaws 8 receive the connectors of the battery or the handles at the ends of the storage battery as the case may be and due to the coil spring 10, the jaws will be retained in gripping relation with respect to the connectors until manually removed therefrom as will be apparent.

75 It is thought from the foregoing description that the advantages and novel features of my invention will be readily apparent.

I desire it to be understood that I may make changes in the construction and in the combination and arrangement of the several 80 parts, provided that such changes fall within the scope of the appended claims.

85 What I claim is:

1. In a storage battery carrier, a handle having forked ends and abutting shoulders 90 adjacent said ends, a pair of co-operating jaws having shanks disposed laterally of said handle and pivoted within said forked ends, said abutting shoulders limiting the inward movement of said jaws, a passage extending longitudinally through said handle and a contractile spring extending through said 95 passage and having its ends connected eccentrically with said shanks to urge said jaws together. 100

2. In a storage battery carrier, a handle having a longitudinally extending passage therethrough, a pair of co-operating jaws having shanks pivoted to the end portions of said handle, a contractile spring extending longitudinally through said passage and completely shielded by said handle, one end of said spring being eccentrically connected with one of said shanks, an insulating member connected to the opposite end of said spring and connected eccentrically to said other shank.

3. In a storage battery carrier, a handle having a pair of recesses extending laterally into the end portions thereof, depending, co-operating jaws having shanks disposed within said recesses and hinged to said handle, said handle having a longitudinal passage communicating with said recesses and an elastic element extending through said passage and having its ends connected eccentrically with the shanks of said jaws to urge said jaws together.

4. In a storage battery carrier, a handle having a pair of recesses extending laterally into the end portions thereof respectively, a pair of cooperating jaws having shanks disposed within said recesses and depending from said handle, pivots extending transversely of said handle and hinging the upper ends of said shanks thereto, said shanks being oppositely inclined outwardly with reference to the longitudinal center line of said handle to cause said jaws to be disposed in offset relation to receive the offset connectors of a storage battery with the center line of said handle disposed in a plane substantially parallel with two opposite walls of said battery.

40. In testimony whereof I affix my signature.
WALTER A. BISHMAN.
